UNITED STATES PATENT OFFICE.

JOHN C. KOPF, OF BELLEVUE BOROUGH, PENNSYLVANIA, ASSIGNOR TO THE DUFF MANUFACTURING COMPANY, OF PITTSBURGH, PENNSYLVANIA, A CORPORATION OF PENNSYLVANIA.

LIFTING JACK.

1,410,579.

Specification of Letters Patent. Patented Mar. 28, 1922.

Application filed March 11, 1921. Serial No. 451,495.

To all whom it may concern:

Be it known that I, JOHN C. KOPF, a citizen of the United States, and a resident of the borough of Bellevue, in the county of Allegheny and State of Pennsylvania, have invented a new and useful Lifting Jack, of which the following is a specification.

The invention relates to ball-bearing screw-jacks and more particularly to the 10 class of jacks used on railroads, known as journal-box or journal jacks. These jacks are required to be used under varying conditions of distance between the chance points of support along the track and the 15 jacking points on the cars, so that frequently after lifting it is found that the lift is not high enough, and that a block must be used, necessitating lowering the load and re-jacking, while at other times there may be difficulty 20 in introducing the jack at all. Because of these conditions, the general endeavor in the design of journal-box jacks has been to keep the fixed height down as much as possible while obtaining the maximum 25 amount of lift, a gain of even a part of an inch being material. The purpose of this invention is to effect a very marked advance in this direction, at the same time securing a construction of notable lightness, strength, 30 and economy of manufacture, all features of special importance in these small, much-used jacks.

A further object is to provide an improved carrying handle which serves a double function.

In the accompanying drawings, forming a part hereof:

Fig. 1 is a vertical section through a journal-box jack embodying the invention; 40 Fig. 2 is a plan view of the base plate; and Fig. 3 is a horizontal section on the line 3—3 of Fig. 1.

The jack has a shell or hollow closed frame 1 having a broad base and a narrow 45 top, the latter formed with a cylindrical bearing 2. Said frame is composed of two parts, the body or shell proper, forming the sides, and a base-plate 3, which is screwed into an internally screw-threaded bottom 50 rim 4 on the wide lower end of the shell. The disk or plate is formed with a raised screw-threaded rim 5 which enters the rim of the shell, and an outwardly projecting flange 6 to abut the bottom of the shell. A 55 pin 7 locks the plate in place.

A hollow cylindrical ram 8, desirably constructed of seamless drawn tubing, and having at its upper end a head 9, is slidably guided in the bearing 2. A customary nut 10 secured in the lower end of the ram cooperates with a screw 11 rotatably supported on the base and extending upward within the ram. On the lower end of the screw is 60 a bevel gear 12, meshed by a driving gear 13 on a horizontal operating shaft 14 journal-naled in a bearing 15 in the side of the shell.

Between the gear 12 and the base-plate is a ball thrust bearing, which sustains the load. Heretofore it has been necessary to make this bearing of two separate hard steel 70 ball plates, of substantial height, with the balls between them, forming a pedestal on which the screw and gear are set above the base. An object of the invention is to practically eliminate this spacing by close coupling the parts without the intervention of ball-plates, thus reducing the spacing substantially to that of the balls themselves, which balls as heretofore are partly received in ball races or pockets. In this way 75 a decidedly longer screw and ram, compared to the height of the jack lowered, can be employed, and thus a greater lifting range secured with equal or less initial height. This is accomplished in the first place by a 80 special construction of the base-plate 3. This plate I make of a drop-forging, having the characteristic toughness of such forgings, and with a ball-race groove 16 pressed directly in its top. The plate is so formed as 85 to present sufficient thickness in the annular region 17 containing the ball-race to withstand the crushing force of the load, inwardly of which, and outwardly between the same and the peripheral region containing 90 the screw rim 5 and abutment flange 6, are thin connecting regions 18 and 19. Such a base-plate while eminently desirable for its strength and lightness, and its relatively 95 small height, is unsuitable because the balls 100 would press into the raceway and render the bearing inoperative. This I find can be overcome and adequate wearing support secured for the balls, heretofore afforded by the special steel ball-plate, by forming a 105 hardened ball-race 20 directly on and from the tough body of the plate. Such an integral ball-race while slight in thickness as compared with a separate ball-plate, can nevertheless be made to extend deeply 110

enough into the forging by ordinary methods of case-hardening to carry the concentrated load pressure of the balls without breaking. There is thus obtained a ball-race too slight 5 in itself to endure the stresses but backed and rendered operative by the body of the structurally advantageous base element. However, because of the screw joint, which is the most durable form of connection between the base and shell, and the most advantageous in respect to keeping down the fixed height, it is not practicable to case-harden the entire surface, or if it is, the hardened part must be removed where the 10 screw-threads 5 are formed. Preferably, after smoothing the groove 16, I electro-plate the base-plate, and then brush off the plating from the groove. Thus, in the hardening process the plating where it remains, and particularly at the region 5, prevents the forged metal from becoming hardened, while the ball-race is formed as described.

The upper ball-race 21 is formed directly on the bottom of the gear 12. This gear is 25 preferably also a drop-forging case-hardened, but might be made, less economically, from steel sufficiently hard throughout.

Jacks of this type are in frequent use in inspecting and removing journal brasses, 30 and must be carried substantial distances by hand, perhaps the length of a long freight. Lightness and a convenient carrying handle are therefore important considerations. The invention provides such a handle, which also 35 serves as a means to keep the ram 8 from turning in the bearing 2. The said handle comprises a bail 22 adapted to be swung vertically above the top of the jack, and having inturned ends 23 which are swiveled 40 in opposed horizontal openings of the top bearing portion 2 of the shell. One of said ends, as seen at the left of Fig. 1, projects through the shell into a longitudinal groove 24 in the exterior of the ram, thus acting as 45 a key.

The numerous advantages of a jack constructed according to my invention will be apparent to those skilled in the art. The elimination of the ball-plates, it may be 50 noted, not only produces a large saving in height and reduces the weight to be carried

about, but is also a substantial economy, as these special steel plates are normally a material item of cost, and frequently after being machined develop defects in the heat treatment, causing them to be discarded after the work has been done upon them. My bottom element is susceptible of rapid and cheap production, and affords both a base-plate and a race-way, embodied in a very light and durable form. The elimination of the lower ball-plate is of further advantage in that these plates have to be fitted fairly closely in their recesses, and it not infrequently happens that they do not seat 65 flat upon the bottoms, because of a fillet at the corners or some unnoticed obstruction in the recess, causing the plate to break when load is applied. These difficulties are now avoided and the manufacture materially 70 simplified by my special base-plate construction having the ball-race on it.

What I claim as new is:

1. A lifting jack having a shell, a ram guided in the top of the shell, a rotary screw 75 within the ram for actuating the same and having a gear on its lower end, a base-plate screwed into the bottom of the shell, and balls interposed between the base-plate and gear, said base-plate having a tough body 80 with an integral hardened ball-race formed thereon and a peripheral screw-thread formed of the unhardened body.

2. A lifting jack having a shell, a ram guided in the top of the shell, a rotary screw 85 within the ram for actuating the same and having a gear on its lower end, a base-plate secured to the bottom of the shell, and balls interposed between the base-plate and gear, said base-plate being a drop-forging having 90 an integral hardened ball-race formed thereon.

3. In a lifting jack, the combination of a shell having a top bearing, a screw-operated ram slidable in said bearing and provided 95 with a longitudinal groove, the top portion of the shell having transverse holes therein, and a carrying handle having ends swiveled in said holes and one of said ends projecting into said groove to constitute a key to keep 100 the ram from turning.

JOHN C. KOPF.
